C. H. REDMAN

GUARD FOR HAIR CLIPPERS

Filed Nov. 7, 1925

INVENTOR
CHARLES H. REDMAN
BY
Geo. L. Wheelock
ATTORNEY

UNITED STATES PATENT OFFICE.

CHARLES H. REDMAN, OF EAST ORANGE, NEW JERSEY, ASSIGNOR TO H. BOKER & CO. INC., OF NEW YORK, N. Y., A CORPORATION OF NEW YORK.

GUARD FOR HAIR CLIPPERS.

Application filed November 7, 1925. Serial No. 67,597.

This invention relates to improvements in guards for hair clippers, and has particular reference to the provision of means for protecting the teeth of a hair clipper against damage while the instrument is out of use.

An important object of the invention is to provide a hair clipper guard which may be readily attached to or detached from a hair clipper to protect the teeth thereof, and having novel means for retaining it upon the clipper.

Another object is to provide such a device which will interlock with the plates of the clipper to prevent its accidental displacement while in use.

Other objects and advantages will be apparent from the following description, taken in connection with the accompanying drawings, wherein a preferred form of the invention is illustrated.

In the drawings, Fig. 1 is a side elevation of a hair clipper with my improved guard applied thereto.

Fig. 2 is a fragmentary top plan view thereof, on an enlarged scale, and illustrating how the guard is locked upon the clipper.

Fig. 3 is a similar view illustrating the necessary movement of the upper clipper plate to facilitate application and removal of the guard.

Fig. 4 is a detail perspective view of the guard per se.

Referring now to the drawings in detail, the reference character 10 designates generally a hair clipper of any ordinary or preferred form, and comprising essentially a lower stationary plate 11, and an upper movable plate 12. Each of the plates 11 and 12 has its front edge serrated to form teeth 13 and 14, respectively, which cooperate to cut hair coming between them when the plate 12 is reciprocated. The plates 11 and 12 are held in close surface engagement by a spring (not shown) contained within a housing 15 which is rigidly mounted on the stationary plate 11, and a handle member 16, having a thumb piece 17, extends from the housing 15. In order to reciprocate the upper plate 12 of the clipper, a lever 18 is provided, pivoted on the stud 19, as is well known to those skilled in the art; and the plate 12 is guided in its reciprocation by means of slots 20 and 21 in which are disposed posts 22 mounted on the stationary plate 11. The parts of the clipper normally occupy a position of

rest, as shown in Fig. 2, the inner edge 23 of the notch 20 abutting the corresponding post 22, against which the plate is held by spring pressure.

In order to protect the teeth 13 and 14 of the clipper from being damaged while the instrument is not in use, I provide a guard which comprises a body portion or plate 24, having an upwardly tapering portion 25 adjacent its front edge, and bent upon itself to form an overhanging lip 26 diverging from the tapering portion 25. The plate 24 is adapted to be positioned close up under the lower plate 11 of the clippers, and the teeth 13 and 14 are disposed between the tapering portion 25 and the overhanging lip 26. Edge-guiding means are provided, preferably in the form of flanges 27 and 28 extending upwardly from the plate 24 and adapted to engage the side edges of the lower clipper plate 11 to prevent lateral displacement of the guard. Integrally formed with the flanges 27 and 28, adjacent the rear end thereof, are a pair of inwardly extending ears 29 and 30 which overlie the clipper plate 11 to prevent the guard from dropping downwardly, and the front edge 31 of the ear 29 is squared for engagement with the rear edge 32 of the upper clipper plate 12. The width of the ear 29 is greater than the distance between the adjacent side edges of the plates 11 and 12, as clearly shown in Fig. 2, and by virtue of this fact the guard may be securely locked in place, and held against accidental displacement in any direction.

When it is desired to apply the guard to a pair of clippers, the lever 18 is operated against the handle 16 to slide the upper movable plate 12 transversely on the lower plate 11 to a position as shown in Fig. 3, whereupon the plate 24 and associated parts of the guard may be slipped into place. The lever 18 may then be released and the guard will be locked in position. To remove the guard, the lever 18 is similarly operated to disengage the edge 32 of the plate 12 from the front edge 31 of ear 29, permitting the device to be slipped off the clipper.

From the foregoing it will be evident that I have provided a hair clipper guard, of simple construction, particularly adapted for use in protecting the teeth of the clipper while being shipped or transported, or in other conditions while not being used. Obviously, the invention is susceptible of mod-

ification, and the right is herein reserved to make such changes as fall within the scope of the appended claims, without departing from the spirit of the invention.

5. What I claim as my invention and desire to secure by Letters Patent is:

1. A hair clipper guard, comprising a plate provided with means on its front edge for guarding the teeth of a hair clipper, 10 edge-guarding means extending transversely of the guarding means, and a locking member overlying a portion of the lower clipper plate and abutting the rear edge of the upper clipper plate when the latter is in its extreme position of rest, said guard being capable of sliding movement in the direction of said edge-guiding means when the upper clipper plate is moved to an intermediate position.
- 15 2. In combination with a hair clipper, a guard plate provided with guarding means engaging over the clipper teeth, edge-means projecting from the plate transversely of the guarding means and engaging the side edges

of the lower cutter plate, and substantially 25 parallel, guiding means on the guard plate, overlapping the side edges of said lower cutter plate adjacent to the back portion thereof, and retaining the guard on the clipper, by virtue of the abutment of one of the 30 guiding means with the rear edge of the upper clipper plate when in its extreme position of rest, and being capable of disengagement by partial movement of the upper clipper plate.

3. In combination with a hair clipper, a plate having guarding means on its front edge for receiving and protecting the clipper teeth, flanges extending from the plate in a direction transverse to the guarding means, 40 said flanges engaging the side edges of the lower cutter plate, and inwardly extending ears integral with the flanges and overlying portions of the lower cutter plate, one of said ears engaging the upper cutter plate to maintain the guard in position on the clipper.

In testimony whereof I affix my signature.
CHARLES H. REDMAN.
